OBSERVATION APPARATUS FOR PRINTING
PRESSES AND THE LIKE

Hans Fischer, Göggingen, near Augsburg, Germany, assignor to Maschinenfabrik Augsburg-Nürnberg A. G., Augsburg, Germany, a corporation of Germany

Application January 25, 1938, Serial No. 186,858
In Germany January 25, 1937

5 Claims. (Cl. 88—14)

My invention relates to apparatus adapted for observing recurring symbols, or the like, appearing on continuous webs of paper or other material while in motion. In devices of this kind, the image of the symbol, or the like is caught by a mirror, which is turned corresponding to the travelling movement of the symbol, or the like in such a way that the direction and position of the light ray reflected by the mirror remains always the same to the observer in every position of the travelling symbol, or the like. After the execution of a partial rotation, the mirror returns to its initial position.

Now, the particular object of this invention is to so design the observation apparatus that it can be readily adjusted to any point of the travelling web and furthermore that it can be readily adapted to various sizes or formats.

Another object of the invention is the provision of observation apparatus of the character mentioned which is so arranged that the distance between the mirror and the traveling web can be readily changed and in which the parts are capable of convenient operation and readily accessible for adjustment and for observation purposes.

The construction of my new apparatus will appear more clearly from the following description with reference to the appended drawings, in which I have shown, by way of illustration, an embodiment of my invention, and in which

Fig. 1 is a longitudinal section through the support from which the observation apparatus is suspended, the latter being shown in elevation; Fig. 2 is a section through the observation apparatus; Fig. 3 is a section through the same taken at right angles to that shown in Fig. 2. Fig. 4 is a section through a portion of the suspension means taken at right angles to that shown in Fig. 1; Fig. 5 is a detail view.

In the drawings, 1 denotes the casing of the observation apparatus which, as shown in Fig. 1, is suspended from the lower end of a perpendicularly depending tubular support 2 formed at its upper end with a hub 3, which encircles a supporting tube 4 horizontally extending through a printing press. The tube 4 is mounted with its ends in the side-walls 5 and 6 of the press. At 7 in Fig. 1 is shown a hollow shaft which is rotatably mounted in the supporting tube 4 coaxially therewith. At 8 and 9 in Fig. 1 are shown two toothed gear wheels, the wheel 8 being secured to hollow shaft 7, whereby the latter may be rotated from a suitable source of power, not shown. At 10 in Fig. 1 is shown a bevel gear

wheel mounted on the hollow shaft 7 for rotation therewith. At 11 is shown a similar bevel gear wheel in mesh with gear wheel 10 and secured to a shaft 12 rotatably mounted within the tubular support 2. The bevel gear wheel 10 may be moved along an elongated key 40 provided on the hollow shaft 7 and engaging a corresponding groove in gear wheel 10. At 13 and 14 in Fig. 2 are shown two bevel gear wheels in mesh with each other, the gear wheel 13 being fast on shaft 10 12, whereby the rotation of the latter is transmitted to a horizontal shaft shown at 15 rotatably journaled in suitable bearings in the casing of the observation apparatus. By means of shaft 15 the oscillatingly mounted mirror shown at 16 in Figs. 2 and 3 is operated, as will be described further below.

In Fig. 1 the horizontal supporting tube 4 is shown provided along its lower side with an elongated slot 17 to enable the shaft 12 to travel in said slot. Now, if it is desired to displace the observation apparatus horizontally along the supporting tube 4, this is accomplished, after first releasing the clamping device 23, shown in Fig. 5, by a corresponding rotation of a hand-wheel shown at 18 in Figs. 1 and 4, which by means of its hub is rotatably mounted on the tubular support 2 and which, by means of a toothed gear wheel 19 rotates a stem shown at 20 in Fig. 4, and which at its upper end carries a toothed gear wheel 21 which meshes with the teeth of a horizontally disposed rack 22 on the supporting tube 4. Therefore, as the hand-wheel 18 is rotated, the toothed gear wheel 21 will move along the rack 22, and thereby the observation apparatus will travel either to the left or to the right in Fig. 1 depending on the direction of rotation of the hand-wheel 18. As the tubular support is displaced to the right or left from the position shown in Fig. 1, the gear 10 is caused to travel axially along the shaft 7 by means of a key 39 which engages an annular slot in the hub portion of the gear 10, the pin 39 being fixed in the hub 3 of the tubular support and being small enough in width so that it may operate along the slot 17 with an adequate spacing from the sides of the slot.

In order to adjust the observation apparatus to a definite length or distance of observation, the clamping device shown at 23 in Fig. 5 is first released whereupon the tubular support 2 can be rocked about the horizontal supporting tube 4 to either side thereof. During this rocking movement the teeth of the gear 21 maintain the meshing relationship with the teeth of the rack 22.

22 since those teeth extend annularly to a sufficient degree to permit this, as will be apparent from the dotted line illustration of the rack teeth shown in Fig. 5. Thus the tubular support 5 2 can be so adjusted that the apex 24 of the observation angle α is moved to 24', the observation angle being the angle through which the mirror is turned during the time any point on the travelling web is kept in view and apparently substantially stationary as viewed by the operator through the observation duct 42 which extends, as shown in Figs. 1 and 4, in a direction parallel to the axis of the tube 4 and in line with a reflector 43 interposed between the mirror 16 and the eye piece. While the observation angle α remains unchanged, the range of the observation apparatus is thereby increased from 10 25, 26 to 25', 26' (Fig. 4). Thus if the distance between points 25' and 26' represents the distance 20 between repetitions of the same symbol on the printed web, that symbol will be viewed by the operator each time the mirror is turned so that the line of sight will follow the web. It should be noted that during the rocking operation 25 of the observation apparatus about the tube 4, the rocking axis coincides with the axis of the operating shaft 1. The change in the range of observation adapts the machine to a larger format obtained from a larger diameter printing roll, it being understood that the R. P. M. 30 of the printing roll bears a definite relationship to the R. P. M. of the gear 8 and shaft 7.

However, since the median plane of the casing of the observation apparatus after the said rocking 35 operation will no longer be parallel with the paper web, the casing must be readjusted so that the line halving the observation angle α again is perpendicular to the traveling web to be observed (Fig. 4). In order to accomplish this, I provide a crank shown in Fig. 3 at 27, whereby I can rotate a worm 28 (Fig. 2) which engages, and imparts its rotation to, a worm-wheel 29. Thereby the casing of the observation apparatus is moved about the axis of the shaft 15 to a position, in which the line halving 45 the observation angle α is again perpendicular to the moving paper web.

On shaft 15 is mounted a toothed gear wheel 30 of a planetary gear. This toothed wheel, by 50 means of an intermediate toothed gear wheel 31 transmits its rotation to a crown-wheel 32, which is coupled with a cam shown at 33 against whose periphery is pressed by a spring (not shown) the lever 34 carrying the mirror 16 (Fig. 3) so that the latter executes a partial rotation. The intermediate gear wheel 31 is secured to a spindle 35 journaled in the worm-wheel 36 so that by a rotation of the latter by means of the worm 37 and a crank shown at 38 the intermediate gear wheel 31 and thereby the cam 33 can be adjusted relative to the shaft 15. In this manner, the observation point can be adjusted in the direction of the moving paper web.

While I have herein described and shown an 65 embodiment of my invention, the same is, of course, not limited to this embodiment, as various modifications may be made without a departure from the essence and gist of the invention.

70 I claim:

1. Apparatus for observing symbols or the like on a traveling web comprising web-guiding means providing an observable path for the web, a mirror for reflecting the light rays from a web 75 traveling in said path, a housing, means support-

ing said mirror in said housing for movement about an axis transverse of said path and in a plane parallel thereto, means for viewing the mirror, means for turning the mirror on said axis to maintain light rays reflected from a point 5 on a web traveling in said path in a substantially stationary position in the viewing means, means supporting said housing for movement about another axis spaced from said first axis and parallel thereto for changing the distance 10 between the mirror and said path, and means for adjusting said housing on said supporting means about another axis spaced from the aforesaid axes and parallel thereto.

2. Apparatus for observing symbols or the like 15 on a traveling web comprising web-guiding means providing an observable path for the web, a mirror for reflecting the light rays from a web traveling in said path, a housing supporting said mirror therein for oscillatory movement about 20 an axis transverse of said path and in a plane parallel thereto, an observation duct extending transversely with respect to the web path in a plane parallel thereto for viewing the mirror from a point outside of the housing, means for 25 turning the mirror to maintain light rays reflected from a point on a web traveling in said path in a substantially stationary position as viewed in the observation duct and for periodically returning the mirror to an initial position, means 30 supporting said housing for movement about an axis spaced from the mirror axis and parallel thereto for changing the distance between the mirror and said path, and means for adjusting said housing on said supporting means about 35 another axis parallel to the aforesaid axes and spaced therefrom.

3. Apparatus for observing symbols or the like on a traveling web comprising web-guiding means providing an observable path for the web, 40 a mirror for reflecting the light rays from a web traveling in said path, a housing supporting said mirror therein for oscillatory movement about an axis transverse of said path and in a plane parallel thereto, means for viewing the mirror, 45 means including a driving shaft and a rotatable cam for turning the mirror on its axis to maintain light rays reflected from a point on a web traveling in said path in a substantially stationary position as viewed in the viewing means and 50 for periodically returning the mirror to an initial position, means supporting said housing for movement about axes spaced from the mirror axis and parallel thereto for changing the distance between the mirror and said path, and adjustable compensating means between the cam and the shaft for changing the timing of the cam.

4. Apparatus for observing symbols or the like 60 on a traveling web comprising web-guiding means providing an observable path for the web, a mirror for reflecting the light rays from a web traveling in said path, a housing supporting said mirror therein for movement about an axis transverse of said path and in a plane parallel 65 thereto, means for viewing the mirror, means for turning the mirror on its axis to maintain light rays reflected from a point on the web traveling in said path in a substantially stationary position as viewed in the viewing means and 70 for periodically returning the mirror to an initial position, an elongated horizontal supporting member extending parallel to the mirror axis and spaced therefrom, a drive shaft in said supporting member, carrying means mounted 75

5 on said supporting member for movement about the axis of the supporting member, means pivotally supporting said housing on said carrying member for movement about an axis parallel to and spaced from said supporting member and from the mirror axis, and means in said carrying member and said housing operably interconnecting said shaft to said mirror turning means.

5. Apparatus for observing symbols or the like
10 on a traveling web comprising web-guiding means providing an observable path for the web, a mirror for reflecting light rays from a web traveling in said path, a housing supporting said mirror therein for oscillatory movement about an axis transverse of said path and in a plane parallel thereto, an observation duct for viewing the mirror from a point exterior of said housing, means for turning the mirror to maintain light

rays reflected from a point on the web traveling in said path in a substantially stationary position as viewed in the observation duct and for periodically returning the mirror to an initial position, a horizontal supporting tube extending 5 transverse of said web path and in a plane parallel thereto, a drive shaft in said tube and concentric therewith, carrying means depending from and mounted on said tube for movement about the axis thereof, means pivotally supporting said 10 housing on the lower end of said carrying means for movement about an axis spaced from the mirror axis and from the tube and parallel thereto, and means in said carrying means and said housing operably interconnecting said shaft to 15 said mirror turning means.

HANS FISCHER.
